[57] CLAIM

The ornamental design for a seat, as shown and described.

DESCRIPTION

FIG. 1 is a front perspective view of a seat showing my new design in the form of a sofa;

FIG. 2 is a side elevational view;

FIG. 3 is a top plan view;

FIG. 4 is a perspective view of the seat as seen from the right and rear of FIG. 1;

FIG. 5 is a front perspective view of a seat showing a second embodiment of my design in the form of a settee;

FIG. 6 is a side elevational view;

FIG. 7 is a top plan view; and

FIG. 8 is a perspective view of the seat as seen from the right and rear of FIG. 5.

FIG. 1

FIG. 2

FIG. 3

FIG. 4

FIG. 5

FIG. 6

FIG. 7

FIG. 8
